US00D967726S

(12) **United States Design Patent** (10) Patent No.: **US D967,726 S**
(45) Date of Patent: **** Oct. 25, 2022**

(54) **DOORBELL MOUNT**

(71) Applicant: **GOOGLE LLC**, Mountain View, CA (US)

(72) Inventors: **Hae Rim Jeong**, San Francisco, CA (US); **Sung Bai**, San Jose, CA (US); **Maj Isabelle Olsson**, Sunnyvale, CA (US); **Étienne Bérubé**, San Francisco, CA (US); **Leslie Greene**, San Francisco, CA (US); **Felix Hugo Antoine**, Mountain View, CA (US)

(73) Assignee: **GOOGLE LLC**, Mountain View, CA (US)

(**) Term: **15 Years**

(21) Appl. No.: **29/763,640**

(22) Filed: **Dec. 23, 2020**

(51) LOC (13) Cl. **10-05**

(52) U.S. Cl.

USPC **D10/118.2**

(57) **CLAIM**

The ornamental design for a doorbell mount, as shown and described.

DESCRIPTION

FIG. 1 is a front perspective view of a doorbell mount showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines illustrate structure or features that form no part of the claimed design. The color forms part of the claimed design.

1 Claim, 4 Drawing Sheets
